UNITED STATES PATENT OFFICE.

EMMA RICKERT, OF AURORA, ILLINOIS.

WAIST.

1,366,942.

Specification of Letters Patent.

Patented Feb. 1, 1921.

Application filed September 23, 1918. Serial No. 255,279.

To all whom it may concern:

Be it known that I, EMMA RICKERT, a citizen of the United States, residing at Aurora, in the county of Kane and State of Illinois, have invented certain new and useful Improvements in Waists, of which the following is a specification, reference being had to the accompanying drawings.

This invention relates to waists, and has for its primary object to provide an improved underwaist for children constructed of tubular, knit material without seams, and a simple and effective arrangement of fabric reinforcing strips to which the drawers or other garments may be secured.

It is another object of my invention to provide an underwaist closed at the front and rear and having separable shoulder strap sections, and suitable fastening means therefor whereby the waist may be easily and quickly donned or removed.

It is also a further general object of my invention to provide an underwaist as above characterized, which is exceedingly simple in its construction, strong, serviceable and convenient in practical use, and capable of manufacture at relatively small cost.

With the above and other objects in view, the invention consists in the improved form, construction and relative arrangement of the various parts as will be hereinafter more fully described, subsequently claimed and illustrated in the accompanying drawing in which similar reference characters designate corresponding parts throughout the several views, and wherein:

Figure 1 is a perspective view of the waist, as applied, and showing the front of the waist and a portion of the side, thereby clearly showing the front tabs 10 and the downwardly extending tabs 12^a.

Fig. 2 is a perspective view of the waist showing the back face thereof and a portion of the opposite side, showing the tabs which extend downwardly and inwardly at the rear, and also showing one of the tabs 12^a.

Referring in detail to the drawing, 5 designates the body of the garment, constructed of tubular, knit fabric. This garment body is formed in one piece, without seams, and the front and rear sides thereof are each provided at its upper end with the shoulder strap sections or attenuations 6.

To the front and rear portions of the body 5 and upon the exterior thereof, the longitudinally extending reinforcing tapes 7 are

securely stitched. Similar fabric tapes 8 are also secured to each side of the waist body and extend upwardly upon the front and rear portions thereof and upon the 60 shoulder strap extensions 6. Suitable button holes are provided in the ends of the front shoulder strap extensions and the ends of the tapes 8, and buttons or analogous fastening elements, indicated at 9, are secured 65 to the other ends of said tapes on the rear shoulder strap extensions for engagement through said button holes.

To each of the reinforcing tapes at the front and rear sides of the waist, short, obliquely disposed, inwardly projecting tabs 10 are secured. These tabs may be free or unconnected to the garment body, or may be suitably stitched thereto, as desired. Preferably, the reinforcing tapes 8, between the 75 tabs 10, are formed with downwardly projecting extension tabs 12^a, as shown in Fig. 2 of the drawing. Said extension tabs 12^a merge integrally into the tapes 8, and these extension tabs 12^a as well as the reinforcing 80 tapes 7, are each provided with buttons, shown at 12, to which the drawers or other garments may be attached.

In the use of the improved waist, the shoulder strap sections are disconnected and 85 the waist slipped downwardly over the child's head into position upon the body. The ends of the shoulder strap extensions 6 are then brought together over the shoulders and connected by means of the buttons 9. The 90 waist is thus securely held in position upon the body, and owing to the omission of front or rear openings, the body of the waist may be constructed to accurately or snugly fit the trunk of the wearer. The provision of 95 the reinforcing tapes obviate stretching of the knit material by the pull of the weight of the other garments which are connected to the waist. The improved waist will, therefore, be very durable and serviceable in 100 practical use, and as only two fastening devices are necessary to connect the shoulder strap extensions it will be manifest that the 105 waist can be very easily and quickly donned or removed. It is apparent, of course, that the 110 waist can be made in larger or smaller sizes for use by misses, adults, or infants, and owing to the very simple construction thereof, it may be manufactured and sold at relatively small cost. It will be noted that the 110 tapes 8 extend downwardly at the front and rear partially toward the sides of the gar-

ment, and are curved and constructed of non-elastic material, and being that the body of the garment is made of elastic knit material, tensions upon the extensions 12^a, due 5 to suspending the lower undergarment thereon would tend to pucker the knit material of the garment under the arms, causing the garment to be uncomfortable on the wearer, and at the same time cause an irritation to the 10 body. However, the tabs 10 which extend inwardly and obliquely at the front and the rear of the garment adjacent the sides are likewise to be under tension by suspending the lower undergarments thereon, and the 15 tension on these tabs acts to counteract the tension on the tapes 8, and prevent the puckering and irritating feeling on the body of the wearer under the arms.

While the preferred form, construction 20 and relative arrangement of the various elements of the improved waist have been herein shown and described, it is to be understood that the device is susceptible of many modifications therein and, accordingly, the privilege of adopting all such legitimate changes as may fall within the spirit and scope of 25 the invention is reserved.

I claim:

An article of wearing apparel comprising 30 a one piece tubular apparel body, adapted to be slipped downwardly over the wearer's

head in position upon the body of the wearer, the apparel body being made of knit elastic material, the upper portions of the front and back of the apparel body having extensions 35 to be connected over the shoulders overlappingly, reinforced non-elastic tapes stitched to the shoulder extensions and arranged in pairs, the tapes of each pair extending downwardly at the front and rear of and slightly 40 toward the sides of the apparel body and curved toward each other and integrally connected, the integrally connected parts of said tapes merging integrally into extension tabs, said extension tabs being located 45 at the lower sides of the apparel body, whereby the tension exerted thereon by a lower undergarment would tend to pucker the knit material under the arm pits, short additional non-elastic tabs stitched to the tapes adjacent where they merge integrally together, said additional non-elastic tabs being located 50 at the front and rear sides of the waist and inwardly and obliquely disposed, whereby the tension of said lower undergarment 55 thereon, acts to counteract tension on the tapes and prevent the puckering of the knit material under the arm pits.

In testimony whereof I hereunto affix my signature.

EMMA RICKERT.
